UNITED STATES PATENT OFFICE.

GEORGE A. RUSH, OF KANSAS CITY, KANSAS.

OSCILLATING VALVE.

1,026,459.

Specification of Letters Patent.

Patented May 14, 1912.

Application filed December 27, 1910. Serial No. 599,392.

To all whom it may concern:

Be it known that I, GEORGE A. RUSH, a citizen of the United States, residing at Kansas City, in the county of Wyandotte 5 and State of Kansas, have invented certain new and useful Improvements in Oscillating Valves, of which the following is a specification.

This invention relates to oscillating valves 10 and my object is to produce a valve of this character which can be used to advantage on locomotives and stationary engines and which will perform its function efficiently and reliably.

15 A further object is to produce a valve of such construction that leakage of steam is prevented, such leakage on locomotives frequently causing accidents as the vision of the engineer is more or less obscured by the 20 escaping steam.

25 A further object is to produce a valve of this character which is balanced and hence operates easily and with practically no friction, under a minimum power pressure and with a minimum supply of lubricating oil.

30 With these general objects in view and others as hereinafter appear, the invention consists in certain novel and peculiar features of construction and organization as 35 hereinafter described and claimed; and in order that it may be fully understood reference is to be had to the accompanying drawings, in which—

Figure 1, is a vertical section on the line 35 I—I of Fig. 2. Fig. 2, is a vertical section on the line II—II of Fig. 1. Fig. 3, is a section on the line III—III of Fig. 1, with the valve omitted. Fig. 4, is a detail perspective view of a circular bushing for the 40 steam chest. Fig. 5, is a detail perspective view of the packing frame.

In the said drawings, 1 indicates a steam cylinder, 2 the steam chest cast integrally with the cylinder and provided with a cylindrical chamber 3, extending at right angles to the longitudinal center of the cylinder, and communicating with the lower part of chamber 3 at opposite sides of its vertical center are steam ports 4 leading to the opposite ends of the steam cylinder. Between 45 said ports is an exhaust chamber 5, vertically below the center of chamber 3, and said exhaust chamber communicates with the exhaust port 6.

50 The heads 7 and 8 of the cylinder are preferably bolted thereto for the convenient

introduction or removal of the piston 9, whose rod 10, extends through head 8 and the packing box 11.

The port for supplying steam to the steam 60 chest, is numbered 12, and is formed in one head or end of the steam chest vertically above the center of such head. 13 is a circular bushing fitting against the head or end of the steam chest provided with inlet 65 port 12, and said bushing has a central opening 14, and an opening 15 through which bolts 16 extend into the adjacent head or end wall to secure the bushing rigidly in position, and the bushing is also provided 70 with an opening 17 communicating with the inlet port.

The opposite end of the steam chest from port 12, is closed by a removable head 18 having a stuffing box 19, in alignment with 75 the journal opening 14. 20 is a hollow cylindrical valve having heads 21 and 22 at opposite ends, the last-named head having an opening 23, and the other an opening 23^a for purposes which hereinafter appear. 80 Projecting from opposite ends of the valve are aligned journals 24 and 25, the former finding a bearing in bushing opening 14 and journal 25 in head 18, and the stuffing box 19, and secured rigidly upon journal 25 is 85 a crank 26, adapted to be operated by any suitable valve gear, not shown.

The valve is provided internally with a V-shaped bridge 27, dividing the interior into a supply chamber 28 and an exhaust 90 chamber 29, the opposite ends of chamber 28 communicating alternately with the ports 4 leading to opposite ends of the cylinder. Chamber 29 alternately connects said ports with the atmosphere through chamber 5, 95 and port 6.

30 are longitudinal grooves at opposite sides of each port 4, and 31 transverse grooves connecting the ends of grooves 30 at opposite ends of said ports. 100

32 are packing strips fitting in grooves 30, and 33 end strips which fit in grooves 31 and preferably connect the ends of strips 32 so as to constitute packing frames, the inner ends of strips 33 of each frame being 105 reduced at 34 to form lap-joint connections. These frames are held pressed yieldingly upward against the valve to form a steam-tight joint therewith, by springs 35, seated in holes 36, communicating with said 110 grooves.

It will be seen by reference to Fig. 1, that

steam is free to pass from chamber 28 around the valve until cut off by the outermost packing strips 32, which surrounding film of steam tends to lubricate the valve, it being also apparent that steam can pass through opening 23 and by bearing against the head 22 of the valve and the head 8 of the steam chest prevent friction between said parts, and hold the valve pressed against the bushing 13, which when worn may be easily removed and replaced by a new one. It will also be apparent that the construction and arrangement of the valve is such that the steam pressure in the chamber 28 acts to balance the valve and thus not only reduce friction to the minimum but insure operation under minimum pressure for a long period of service.

In actual practice the steam enters through port 12 and opening 17 of the bushing and passes from chamber 28 of the valve through the communicating port 4 to the cylinder and forces the piston 9 toward the opposite end or head of the cylinder. In traveling in the direction indicated the piston forces the exhaust steam from the cylinder through the other port 4 and communicating exhaust chamber 29 into chamber 5 from which it escapes through the exhaust port 6. When the piston movement in the direction indicated ceases, the position of the valve is reversed and the exhaust chamber 29 establishes communication between the other port 4 and chamber 5 and opens communication between chamber 28 and the opposite end of the cylinder to admit steam to such end to effect reverse action of the piston. As the piston or the wear strips are reduced in thickness from frictional contact, the springs 36 by upward pressure on such strips maintains the steam-tight relation of the latter with the valve.

Should it be desired to disconnect one side of the engine, the valve at that side may be inverted so that the port 17 of the bushing shall be blanked or covered and thus prevent steam entering the steam chest.

From the above description it will be apparent that I have produced an oscillating valve embodying the features enumerated as desirable and I wish it to be understood that I do not desire to be restricted to the exact

details of construction shown and described as obvious modifications will suggest themselves to one skilled in the art.

55

I claim:

1. The combination with a cylinder and a cylindrical steam chest having ports connecting opposite ends of the former with the latter at opposite sides of its center and an exhaust port between the first-named ports connecting the steam chest with the atmosphere and having longitudinal grooves between the said ports and outward of the first-named ports and transverse grooves connecting the ends of the longitudinal grooves, of a packing frame fitting in the grooves surrounding each of the first-named ports, said packing frames having inwardly projecting lapping extensions at their ends occupying the central portions of the said transverse grooves, and springs underlying said frames and tending to press them upwardly out of said grooves.

2. The combination with a cylinder and a cylindrical steam chest having ports connecting opposite ends of the former with the latter at opposite sides of its center and an exhaust port between the first-named ports connecting the steam chest with the atmosphere and having longitudinal grooves between the said ports and outward of the first-named ports and transverse grooves connecting the ends of the longitudinal grooves, of a packing frame fitting in the grooves surrounding each of the first-named ports, said packing frames having inwardly projecting lapping extensions at their ends occupying the central portions of said transverse grooves, springs underlying said frames and tending to press them upwardly out of said grooves, and an oscillatory valve fitting in the steam chest and provided with a supply chamber and an exhaust chamber, and an inlet opening through which steam passes into the supply chamber, said valve being engaged peripherally by the spring actuated packing frames.

In testimony whereof I affix my signature, in the presence of two witnesses.

GEORGE A. RUSH.
